[57] CLAIM

The ornamental design for a child's car seat, as shown and described.

DESCRIPTION

FIG. 1 is a front perspective view of a child's car seat showing my new design;

FIG. 2 is a left side elevational view;

FIG. 3 is a top plan view;

FIG. 4 is a right side elevational view;

FIG. 5 is a bottom plan view;

FIG. 6 is a front elevational view; and,

FIG. 7 is a rear elevational view thereof.

FIGS. 3 through 7 have been drawn to a smaller scale with respect to FIGS. 1 and 2.

FIG. 1

FIG. 2

FIG. 3

FIG. 4

FIG. 5

FIG. 6

FIG. 7
